UNITED STATES PATENT OFFICE.

MARTIN C. BERSTED, OF CHICAGO, ILLINOIS.

GREASE GUN.

Original application filed November 27, 1920, Serial No. 426,722. Divided and this application filed September 3, 1921. Serial No. 498,590.

This application relates to improvements in grease guns and is a division of application No. 426,722, filed November 27, 1920.

The object of this invention is to generally 5 improve the construction of grease guns and to render every operation more satisfactory and reliable.

Special objects of the invention are to provide a structure in which the piston can be 10 quickly returned to the back of a barrel whereby much time is saved in charging the gun; to provide a connection for the nozzle cap that will not leak; and to provide a grip on the barrel that will enable the operator to 15 maintain his hold on the gun.

In the accompanying drawings illustrating a selected embodiment of the invention

Fig. 1 is an elevation of the gun;

Fig. 2 is a longitudinal section of the 20 grease gun.

Fig. 3 is a section substantially similar to Fig. 2 showing the parts in position for return of the plunger to initial position.

Figs. 4, 5 and 6 are sections on the lines 25 4—4, 5—5 and 6—6 respectively of Fig. 2.

Fig. 7 is a detail elevation.

The body of the gun or pump comprises a barrel 17 ferruled at 18 between its ends to provide a firm and effective grip. It has 30 been customary heretofore to knurl the barrel so that it may be firmly gripped and while this answers well under some conditions the knurling frequently becomes filled with dirt and grease so that it is not effective for the 35 purpose intended. I have found that the ferruling in or about the manner shown provides a permanent and effective grip even when the barrel is greasy as it is very apt to become around a garage or other shop. The 40 discharge end of the barrel is provided with a bevel edge 19 and the cap 20 has a bevel seat 21 to receive the bevel edge 19 and form a tight seal. The cap 20 has a flange 22 which enters the barrel 17 and threadedly 45 engages the barrel. The cap has an interior thread 23 at its outer end to receive the connecting tube. A plunger is carried by a screw stem 24 within the barrel and this plunger comprises an upper washer 25, a 50 lower washer 26 and an interposed leather disk 27 which makes tight engagement with the wall of the barrel and prevents the grease from passing above the plunger. The upper washer 25 has radial ribs 25' for 55 strength and is mounted on the inner end of

the stem. Below the washer 25 the stem has a bevelled or tapered groove 28 and the leather disk has a hole therein of less diameter than the diameter of the end of the stem but which will permit the disk to be forced 60 on to the stem after which the edges of the hole will seat in the tapered or bevelled groove. Then the outer washer 26 is put on the stem and the latter is spun over at its inner end 24' to secure the plunger on the 65 stem. With this construction the stem will turn easily in and relatively to the plunger head.

At the upper end of the barrel there is an off-set seat 29 of hexagon shape to receive 70 the body of a feed nut the lower part 30 of which is hexagon shape to interlockingly engage the hexagon seat 29 and the upper part 31 of which is reduced in diameter and is circular in shape to engage the circular opening 32 in the end of the barrel above the hexagon seat 29. After the nut body has been engaged with the seat 29 a shoulder 33 on the outer edge of the nut body is spun over upon the outer end of the barrel to make 75 a close, tight, fit. Two complementary members 34 are pivotally mounted at 35 in ears 36 on the under side of the nut body and these members project up through recesses 80 in the nut body and above said body and 85 are shaped and threaded to embrace and threadedly engage the threaded stem 24. These members have a limited pivotal movement which enables them to be swung into and out of operative engagement with the 90 stem. The members are limited in their inward movement by shoulders 38 thereon engaging the under side of the nut body and they are limited in their outward movement by engagement with the walls of the recesses 95 37. The shoulders 38 not only limit the inward swinging movement of the members 34, but they also properly position the members for engagement with the stem. I prefer to cut away the shoulders 38 at their corners, shown at 38', to allow for the accumulation of grease or dirt which might otherwise interfere with the proper adjustment or 100 swinging movement of the members 34 and prevent them from operatively engaging the stem, and for the same reason I prefer that these members should not abut each other but that there should be a limited space between their adjacent edges.

The threaded members are held in opera- 110

5 tive engagement with the stem by a cap 39 which snugly engages the upper ends of the threaded members and is flared at its outer end 40 to cover the recesses 37 in the
10 nut body. This clamping cap or collar is adapted to slide freely on the stem but when engaged with the threaded members 34 forming the plunger feed nut it will rigidly hold them in operative threaded engagement
15 with the stem until it is released by simply lifting it from engagement with the feed nut members. I prefer, however, that the threaded members should be slightly enlarged at their upper ends and also that the cap
20 should be provided with an interior groove 41 to accommodate this enlargement. This prevents accidental disengagement of the cap from the threaded members of the nut, and consequently prevents accidental disengagement
25 of the threaded members of the nut from the stem. A handle 42 is secured to the upper end of the stem by a hub 43 which has a tapered lower end 44 and a slight groove 45. When the cap 39 is disengaged
30 from the threaded members 34 of the feed nut it may be thrust up upon the tapered end of the hub into engagement with the groove 45 to stay there while the plunger is being returned to initial position (Fig. 3).
35 It will be noted that in the ordinary forward feed of the plunger the cap 39 will hold the threaded members in operative engagement with the screw stem and this arrangement of the parts will continue until it is desired to refill the barrel with grease whereupon the plunger is returned to initial

position, the barrel cap 20 is removed and the barrel is refilled. To speedily return the plunger to initial position the cap 39 is disengaged from the feed nut members 34 so that the latter may swing to open position (Fig. 3), and then the screw stem and plunger may be quickly returned to initial position without necessitating unscrewing movement of the stem.

The gun may be equipped with any sort of flexible conduit but I prefer to use that set forth in my accompanying application, Serial Number 498,591, filed September 3, 1921.

I am aware that changes in the form and proportion of parts, and in the details of construction of my invention may be made without departing from the spirit or sacrificing the advantages thereof, and I reserve 55 the right to make all such changes as fairly fall within the scope of the following claims.

I claim:

1. A grease gun comprising a barrel having a round opening in its upper end and an angular seat below said opening, and a nut having a angular part to fit said seat and a round part to fit said opening. 60

2. A grease gun comprising a barrel having a round opening in one end and an angular seat below said opening, a nut having an angular part to fit said seat and a round part to fit said opening, and a shoulder on said round part spun over to engage the end of the barrel. 65 70

MARTIN C. BERSTED.
